UNITED STATES PATENT OFFICE.

HERMAN E. COLE, OF BINGHAMTON, NEW YORK.

IRONING-STAND.

No. 866,259.

Specification of Letters Patent.

Patented Sept. 17, 1907.

Application filed August 6, 1906, Serial No. 329,420.

To all whom it may concern:

Be it known that I, HERMAN E. COLE, a citizen of the United States, residing at Binghamton, New York, have invented certain new and useful Improvements 5 in Ironing-Stands, of which the following is a specification.

My invention relates to an improved folding support for ironing boards, and the object of the invention is to provide a simple, durable, economical, and efficient 10 form of stand which will not only support the ironing board but will also provide a convenient place for the deposit of the ironed articles and which may be readily folded into compact form when not in use.

With these and possibly other objects in view the 15 invention includes the novel features of construction and arrangement and combination of parts hereinafter described and particularly set forth in the appended claims.

The invention is illustrated in the accompanying drawings, in which,—

Figure 1 is a side elevation. Fig. 2 an end view, and Fig. 3 is a view with the ironing board and the support folded.

In these drawings the numerals 1, 1, designate two 20 cross bars which connect the upper ends of the standards 2, 2, and are designed to support the ironing board which is laid thereon and held against slipping off by the ends of said standards which project slightly above the cross bars as shown. The standards 2 at each end 25 are also connected by crossed diagonal braces 4 by which they are firmly braced. The standards and connected braces thus form a folding frame at each end

which is pivotally connected to the side bars 6 of a rectangular frame composed of side and end bars 6 and 7 and connecting slats 9. The standards 2 rest against 35 the outer faces of the side bars to which they are pivotally connected by bolts 10.

A rectangular frame indicated at 8, and preferably braced by diagonal bars 8' is hinged to the rear side bar of the frame 6 and is of such a size as to be capable 40 of being folded down into the same. The upper corners of this frame 8 are provided with hook or like fastening devices designed to engage the upper ends of the standards 2 to connect the parts, whereby the upper ends of the standards are firmly braced.

The ironing board is made of such a width and length that it may be laid on the cross bars of frame 6 when the parts are folded down into the position shown in Fig. 3.

Having thus described my invention what I claim 50 is:—

A support for ironing boards and the like, comprising a rectangular frame, a pair of connected standards hinged to the corners of the frame at each end and extending above and below the frame, and a rectangular folding bracing 55 frame having one of its longitudinal edges hinged to one of the longitudinal edges of said rectangular frame and foldable upon said frame, and means for holding the foldable frame in vertical position between the standards, substantially as described.

In testimony whereof, I affix my signature in presence 60 of two witnesses.

HERMAN E. COLE.
